DESK CLOCK

William Anthony Hilliard, Danvers, Mass., assignor to Bunker Ramo Corporation, Oak Brook, Ill.

Filed Mar. 2, 1973, Ser. No. 337,403

Term of patent 14 years

Int. Cl. D10—01

U.S. Cl. D10—25

FIG. 1 is a top plan view of a desk clock showing my new design;

FIG. 2 is a rear elevational view thereof;

FIG. 3 is a right side elevational view thereof;

FIG. 4 is an enlarged top left perspective view thereof.

I claim:

The ornamental design for a desk clock, as shown.
